CLAIM

The ornamental design for a double tongue soccer boot/training shoe, as shown and described.

DESCRIPTION

FIG. 1 is a top plan view of a double tongue soccer boot/training shoe, showing my new design in the open position;

FIG. 2 is a top plan view thereof, in the closed position;

FIG. 3 is a bottom plan view of FIG. 2;

FIG. 4 is a side view of FIG. 2;

FIG. 5 is a rear view of FIG. 2;

FIG. 6 is a perspective view of FIG. 2;

FIG. 7 is a perspective view of FIG. 1;

FIG. 8 is a plan view showing a ball agitator of the double tongue soccer boot/training shoe;

FIG. 9 is a front view of FIG. 8;

FIG. 10 is a side view of FIG. 8;

FIG. 11 is a perspective view of FIG. 8; and,

FIG. 12 is another perspective view of FIG. 8.

The solid black areas in the Figures represent the color black.
